HAND TOOL

Margaret M. Davenport, Los Angeles, Calif.

Application May 1, 1937, Serial No. 140,216

2 Claims. (Cl. 30—356)

This invention relates to hand tools and particularly to small knives such as are used for paring vegetables and fruit, cleaning fish, particularly shell fish such as shrimp, and for general kitchen use, although it has numerous other applications as well.

An object of the invention is to provide a simple and inexpensive hand tool having a cutting edge adaptable for general cutting purposes to which a knife is put, in combination with a gouging point so directed as to be useful in place of the cutting edge without necessitating shifting the tool to a different position in the hand.

I achieve these objects by so bending the end 15 of a pointed knife blade as to cause the extreme tip of the blade to extend at right angles to the length of the blade and in the direction of one lateral edge of the blade, the mentioned lateral edge of the blade being sharpened to constitute 20 a knife edge extending substantially from the handle to the bent tip portion.

A full understanding of the invention can be had from the following detailed description of a specific embodiment of the invention which refers to the drawing.

In the drawing:

Fig. 1 is a side view of a complete tool in accordance with the invention.

Fig. 2 is a top view of the tool looking at the 30 rear edge of the blade.

Fig. 3 is a side view of a blank from which the blade portion of the tool may be formed.

Fig. 4 is an end view of the tool shown in Fig. 1.

Referring to Figs. 1 and 2, the tool therein 35 depicted comprises a blade member 1 joined to a handle 2. In accordance with the general practice, the handle 2 may consist of two handle members 3 riveted to the opposite sides of the blade member over a substantial portion of the length of the blade member. However the particular mode of attachment of the handle to the blade is immaterial, and in the present invention the blade may or may not extend through the handle.

As shown in Fig. 3, the blade is formed from 45 a flat blank of thin steel having one edge 4 beveled or ground so that it is sharp and constitutes a cutting edge which, preferably, extends from closely adjacent the end of the handle 2 to a point 5 adjacent to but spaced from the outer tip of the blank. The blade is preferably tapered on both edges substantially from the end of the cutting edge 5 to the extreme tip.

The tool shown in Figs. 1 and 2 is fabricated 50 from the blank shown in Fig. 3 by first twisting

the blade about its longitudinal axis through an angle of 90° between the longitudinal limits 7, 5 and 8. Thus after the bend is completed the line 7 on the blade extends straight across the blade but at right angles to the plane of the main portion of the blade. However, the twisting of the blade causes the rear edge 9 to begin to bend substantially at the point 8 whereas the front edge deviates from the point 5, thereby producing a more or less sharp fold 10 extending diagonally 10 across the blade from point 5 to point 8. The twisting also tends to produce another sharp bend along a line 11 (Fig. 2) extending from the back edge of the blade at the longitudinal point 7 thereon to the front edge of the blade at a 15 point longitudinally intermediate points 5 and 8.

The extreme tip portion of the blade beyond the line 7 is then folded at right angles so that the extreme tip 12 of the blade extends substantially at right angles to the longitudinal axis of 20 the blade and in the direction of the cutting edge 4, as shown in Fig. 1.

It is to be understood, of course, that the bending operations described are performed on the blade while the latter is in relatively soft, flexible 25 condition, and the material of the blade thereafter hardened in any suitable manner. It may usually be desirable to effect the bending of the blade while it is in a heated condition.

The completed tool as shown in Fig. 1 is very 30 convenient for use in operations requiring alternate cutting or paring and gouging because the tool can be used either for cutting or gouging without shifting the position of the tool in the hand.

Another advantage of the construction disclosed is that since the point 12 projects in the direction of the width of the blade, the blade is very strong with respect to bending forces resulting from a gouging operation which requires 40 considerable pressure to be exerted by the point 12. Thus I am aware that it is old to provide blades with a gouging point in which the tip of a flat blade is simply bent laterally. With such tools if it is attempted to place much pressure 45 on the gouging point the blade itself bends because of its flexibility in the direction of its thickness. However with my construction, in which the point is directed in the direction of the width of the blade, great forces can be exerted on the point 12 from the handle 2 because 50 of the great rigidity of the blade in the direction of its width.

It is to be understood that the construction described is not limited to knives. Thus where 55

a cutting edge is not required a structure exactly similar to that disclosed may be employed but without a cutting edge on the blade. Furthermore, where the cutting edge is not desired or required the total length of the blade may be greatly reduced, thereby bringing the gouging point 12 closer to the handle.

Although the invention has been explained by describing a particular preferred construction, 10 it is to be understood that the same general structure can be obtained with other methods of manufacture and the invention is to be limited only to the extent set forth in the appended claims.

15 I claim:

1. A hand tool of the type described, comprising a handle and a thin blade member secured to and extending from the handle, said thin blade member converging to a pointed portion at the

outer end and the blade member being twisted through an angle of 90° adjacent to but back of the tip portion and the tip portion being bent in the direction of the thin dimension of the blade immediately beyond said 90° twist whereby said tip portion is symmetrically disposed with respect to the plane of said blade.

2. A hand tool of the type described, comprising a handle and a thin blade member secured to and extending from the handle, said thin blade member merging at its outer end into a flat tip portion lying in a plane perpendicular to the plane of the blade member, said flat tip portion being substantially triangular in shape, a base portion of the triangular tip being secured to said blade and an opposite point of the triangle lying substantially in the extended plane of the blade.
